UNITED STATES PATENT OFFICE

2,484,922

WINDOW VENTILATOR

Lee G. Allen, Memphis, Tenn.

Application September 6, 1946, Serial No. 695,157

3 Claims. (Cl. 98—99.1)

1

This invention relates to the control of ventilation and the avoidance of drafts in rooms, and more particularly to the provision of means for securing window ventilation without objectionable drafts.

Windows of conventional type normally have no provision for control or deflection of air gusts so that the occupant of a room on a warm, yet breezy day is often faced with the choice of leaving the window closed, thus foregoing any ventilation, or of opening it and suffering the consequent annoyance of having papers, curtains and other light appurtenances blown about the room.

To remedy this, it is well known to provide deflectors, attached in various ways to the window frame or sill, which cause air entering through the window to be diverted in an upward direction. Such deflectors achieve, to a greater or less extent, their object of avoiding direct drafts while providing a certain amount of ventilation. However, they are universally subject to the disadvantage that a very considerable portion of the air striking the window opening is deflected so as to be prevented from entering the room, and to the additional disadvantage that the air occupying the lower portion of the room is not disturbed except on very windy days or when there is a sizable thermal difference between the inside and outside air.

It is a primary object of my invention to provide simple and inexpensive means for effectively controlling window drafts without interfering to any appreciable extent with natural ventilation. It is a further object to provide a draft deflector which directs entering air both upwardly and downwardly so as to produce movement of the air in all parts of the room. It is a still further object to permit full advantage to be taken of any breeze which may be blowing, while positively preventing undesirable drafts which are apt to disturb papers and the like and which may also be harmful from a health standpoint. Still other objects will be apparent from the complete description of this invention which follows.

These objects are accomplished by my novel device which consists of a pair of flat rectangular members which are mounted on suitable end plates so as to lie inside and across the window opening. The rectangular members are angularly disposed to one another and are engaged along a longitudinal edge of each, so that a plane angle is formed pointing toward the window opening. The resulting wind deflector is so mounted that a small opening is left between

the lower member and the window sill, with the result that air currents are permitted to enter the room partly above and partly below the deflector, being directed respectively toward the ceiling and toward the floor. In this way, direct drafts are avoided, yet substantially all of the air approaching the window opening is permitted to enter the room.

To obtain a more complete understanding of my device, reference may be had to the accompanying drawings.

Figure 1 is a perspective view, from the interior of a room, of a window on which has been mounted my wind deflector.

Figure 2 is a perspective view on a larger scale of the arrangement of the deflecting members and their position with respect to the end plate.

Figure 3 is an elevation of the end plate, showing the position of the deflecting members.

Figure 4 is an elevation of the end plate, showing an optional arrangement of the deflecting members, particularly designed to reduce the amount of water entering the window during a rain, although with some sacrifice of ventilation.

Referring to the drawings in detail, Figure 1 shows a conventional guillotine-type window, viewed from the interior of the room. End plates 1 are attached, removably if desired, either to the window jamb 2 or to the sill 3 or to both, and are disposed adjacent and parallel to the jamb. The outer edge of the end plates lies just inside the edge of the window sash groove 4 in order that the sash 5 may be lowered and the window closed without any interference from the deflector or end plates.

The deflector proper consists of an upper plane rectangular member 6, which slants inwardly and upwardly away from the window opening, and a lower plane rectangular member 7, which slants inwardly and downwardly away from the opening. The two members are joined together at their outer longitudinal edges, and are attached to and held by the end plates 1, as clearly shown in Figure 3. They may be attached to the end plate by any desired means, such as through the use of small angles, by nailing, or by inserting them into grooves cut in the end plates and securing them by nailing. This latter method is that which is shown in the drawings.

It will be seen from Figures 1, 2 and 3 that a small opening is left between the lower edge of the deflector member 7 and the window sill 3, to permit air to enter the room under the deflector in a downward direction. The actual size

of this opening may vary considerably according to the size of the window and the desires of the builder, but I have found that with the average window a spacing of approximately one inch gives good results.

Should it be desired to provide protection against rain, with some attendant sacrifice in ventilation, a construction such as is illustrated in Fig. 4 may be used. This view shows an end plate 8 and a sectional representation of the deflecting members 9 and 10, in which the upper deflecting member 9 is extended outwardly over and beyond the outer edge of the lower deflecting member 10 and thus provides a shield to deflect rain drops outwardly. This construction permits leaving the window open during light rains, so as to admit air while keeping out the rain. Such a deflector may be built rigidly in this form or, alternatively, may be constructed so that the upper member 9 can be adjusted either in the position shown in Figure 4 or that illustrated in the other figures. This may be done by providing separate grooves in the end plates to accommodate the deflecting member in the two positions or by providing removable stops for inserting in the grooves, or by any other desired means.

The shape of the end plates may vary considerably without effect on the operation of this device. Figures 1, 2 and 3 show a rectangular plate, while Figure 4 shows a plate having its inner side partially cut away. Other variations may be readily imagined.

My deflector may be constructed of wood, metal, plastic and the like, or of a combination of materials, as for example, the end plates and lower deflecting member may be made of metal and the upper deflecting member comprise a glass panel.

While for the sake of clarity and simplicity I have described and illustrated my deflector according to specific embodiments thereof, it is to be understood that many changes may be made without departing from the spirit or scope of my invention and that I do not desire to be limited to the specific embodiments except as defined in the appended claims.

I claim:

1. The combination with a window comprising an inner sill extending inwardly of a room, of a ventilator comprising a pair of vertical end plates disposed on the sill and a pair of deflector plates

connected at their ends to the end plates and disposed in longitudinal edge abutment with one another, one of the deflector plates being inclined upwardly of the room and the other downwardly toward the floor, with the apex of the abutting deflector plates directed outwardly and the bottom edge of the lower deflector plate spaced above said sill.

2. The combination with a window comprising an inner sill extending inwardly of a room, of a ventilator comprising a pair of deflector plates positioned above and extending longitudinally of said sill and having their ends attached at the sides of the window, said plates being disposed in longitudinal edge abutment with one another, one of the deflector plates being inclined upwardly of the room and the other downwardly toward the floor, with the apex of the abutting deflector plates directed outwardly and the bottom edge of the lower deflector plate spaced above said sill.

3. The combination with a window comprising an inner sill extending inwardly of a room, of a ventilator comprising a pair of deflector plates positioned above and extending longitudinally of said sill and having their ends attached at the sides of the window, said plates being disposed in angular, longitudinally abutting relation, one of the deflector plates being inclined upwardly of the room and the other downwardly toward the floor, the abutting portions of the deflector plates being directed outwardly, the bottom edge of the lower deflector plate being spaced above the sill, and the lower edge of the upper plate projecting beyond the adjacent edge of the lower plate to provide rain-deflecting means.
